A. L. ROGERS

STEPLADDER

Filed April 21, 1922

Attorney

UNITED STATES PATENT OFFICE.

ALONZO L. ROGERS, OF WALKERTON, INDIANA.

STEPLADDER.

Application filed April 21, 1922. Serial No. 555,899.

To all whom it may concern:

Be it known that I, ALONZO L. ROGERS, a citizen of the United States, residing at town of Walkerton, in the county of St.

5 Joseph and State of Indiana, have invented certain new and useful Improvements in Stepladders, of which the following is a specification.

10 My invention relates to improvements in step ladders and has particular reference to the back or supporting leg structure thereof.

An important object of the invention is to provide a back or leg structure which is powerfully braced to render the same stiff 15 and strong, without complicating the construction.

Other objects and advantages of the invention will be apparent during the course of the following description.

20 In the accompanying drawings forming a part of this specification and in which like numerals are employed to designate like parts throughout the same,

Figure 1 is a perspective view of a step 25 ladder embodying my invention, and,

Figure 2 is an elevation of the rear side of the back or leg structure.

In the drawings, wherein for the purpose of illustration is shown a preferred embodiment of my invention, the numeral 5 designates the front of the step ladder, which front may be of any well known or preferred construction, embodying legs 6, connected by rounds 7. The invention is in no sense restricted to the use of the particular form of front shown, as the back, embodying the invention, may be used in connection with various types of fronts.

30 The back or leg structure embodies legs 8, connected at spaced intervals by horizontal bars 9. The upper ends of the legs 8 are apertured to pivotally receive the uppermost round 10, whereby the front and back of the ladder are connected. The front and back

45 may be prevented from spreading by any suitable means, and for the purpose of illustration, I have shown a flexible element or rope 11 connecting these parts.

To stiffen and strengthen the back or leg structure, I provide longitudinally curved 50 truss braces 12, arranged inwardly of the legs, and connected with the intermediate bar 9, at 13. The upper and lower ends of these truss braces contact with the legs 8, and are secured thereto by any suitable 55 means, and for the purpose of illustration, I have shown straps 14, which surround the ends of the truss braces and the legs, and securely connect them. If desired, the ends of the truss braces may be further connected 60 with the legs 8 by means of nails or the like.

It is to be understood that the form of my invention herewith shown and described is to be taken as a preferred example of the same, and that various changes in the shape, 65 size, and arrangement of parts may be resorted to without departing from the spirit of my invention or the scope of the subjoined claim.

Having thus described my invention, I 70 claim:

A step ladder comprising a front, and a back pivoted to said front, said back comprising legs, spaced transverse bars disposed upon the edges of said legs and connected therewith, longitudinally curved truss braces arranged between said legs and disposed in the plane of said legs with their edges substantially parallel with the edges of the legs, the ends of the braces contacting with the 75 inner faces of the legs, means for connecting the intermediate transverse bar with the intermediate portions of said braces, and straps surrounding the ends of the braces and the legs. 80

85 In testimony whereof I affix my signature.

ALONZO L. ROGERS.
